UNITED STATES PATENT OFFICE.

JAMES A. BROWN, OF BRISTOL, TENNESSEE.

CHUTE.

Application filed April 9, 1927. Serial No. 182,425.

This invention relates to certain improvements in chutes and it is an object of the invention to provide a structure of this kind adapted to be employed in connection with a window opening and which comprises a plurality of relatively movable members which, when folded or compacted, permits the device to be employed as a shutter or closure member for the window opening. Another object of the invention is to provide a device of this kind comprising a plurality of relatively movable members which, when extended, provide a chute operating to facilitate the storage of coal or the like within a cellar or kindred storage place.

The invention consists in the details of construction and in the combination and arrangement of the several parts of my improved chute whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in elevation illustrating a chute constructed in accordance with an embodiment of my invention and in a position to serve as a shutter or closure member for a window opening;

Figure 2 is a vertical sectional view of the device as herein disclosed and extended or adjusted for use as a chute;

Figure 3 is a vertical sectional view taken through the structure as illustrated in Figure 1;

Figure 4 is a view partly in section and partly in top plan illustrating the members of the device partly folded or compacted;

Figure 5 is a view similar to Figure 4 showing additional members in folded or compacted adjustment;

Figure 6 is a horizontal sectional view taken through the upper portion of Figure 1;

Figure 7 is a fragmentary view in per-

spective illustrating a portion of the means for holding the structure in operative or working position as a chute.

As herein disclosed, F denotes a window frame adapted to be arranged within a wall structure W in a well known manner.

Disposed across the lower portion of the frame F is a rod 1 which is also directed through the lower portion of a solid shutter or closing member 2 whereby said shutter or member 2 is hingedly supported with respect to the frame F whereby the same may be readily moved into open or closed position.

When in closed position the shutter or member 2 may be effectively maintained in such position against unauthorized opening through the medium of a lock 3 engaged with the outstanding staple 4 carried by the outer end portion of the member or shutter 2, said staple 4 and lock 3 coacting in a well known manner with a conventional hasp 5 secured to the upper member of the frame F.

Hingedly connected, as at 6, with each side portion of the shutter or closure member 2 is a straight marginal portion of a side wing 7. This side wing 7 is preferably in the form of a quadrant of a circle with the second straight edge arranged adjacent to the hinged marginal portion of the shutter or member 2.

Hingedly connected, as at 8, to said second named straight edge marginal portion of the side wing 7 is a second wing 9 also preferably a quadrant of a circle and substantially a duplicate of the associated wing 7.

One of the wings 9 is hingedly connected, as at 10, with an upstanding side flange 11 disposed along a side marginal portion of a chute plate 12 while the second wing 9 along its inner straight edge marginal portion is provided with the hook members 14 adapted to be detachably engaged with the opposite side marginal portion of the plate 12 when the wings 9 are extended into working position. These hook members 14 are preferably engaged through the openings 15 provided in the side marginal portion of the chute plate 12 remote from the hinges 10.

When the wings 7 and 9 together with 100

the chute plate 12 are extended into working position a hook member 16 carried by the upper portion of each of the wings 7 is operatively engaged with an eye member 17 or the like carried by the upper portion of the frame F whereby the device is maintained in desired position for use as a chute to facilitate the delivery of coal or the like within a cellar or kindred place of storage.

- 10 In compacting or folding the device the hooks 14 carried by one of the wings 9 are first disengaged from the chute plate 12 whereupon said wing 9 together with an associated wing 7 are swung inwardly and downwardly to overlie the closure member or shutter 2 and chute plate 12 as indicated by broken lines in Figure 4. The wing 9 is then swung on its hinges 8 to overlie the adjacent wing 7 as indicated in Figure 5.
- 15 The wings 7 and 9 at the opposite sides of the member or shutter 2 and plate 12 are then swung inwardly to overlie the previously folded wing 7 and plate 12 whereupon the plate 12 and the overlying wing 9 are swung inwardly to overlie the member or shutter 2 resulting in a complete folding or compacting of the device as particularly illustrated in Figures 2 and 6. The member or shutter 2 with the folded wings and plate 12 are then swung upwardly into closed position with respect to the frame F.

To assure the wings 7 and 9 together with the plate 12 being maintained in desired folded relation while the member or shutter 2 is in closed position, I find it of advantage to employ the elongated rod 18 freely connected, as at 19, to a side member of the frame F at the upper portion thereof, the opposite extremity of the rod being provided with a hook member 20 to engage within an eye member 21 or the like carried by the second side member of the frame F.

- 35 As before explained, the closure member or shutter 2 may be effectively held in closed position and against unauthorized opening through the instrumentality of the lock 3, staple 4 and hasp 5.
- 40 It is also to be understood that before the device is folded or compacted it is required that each of the hook members 16 be disengaged from the eye member 17 or the like.

- 45 From the foregoing description it is thought to be obvious that a chute constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation 60 of the several parts herein shown in carry-

ing out my invention in practice except as hereinafter claimed.

I claim:

1. In combination with a window frame, a closure member for said frame, means for connecting an end portion of the closure member to the frame to permit said closure member to have swinging movement relative to the frame into open or closed position, wings pivotally connected to the side 75 marginal portions of the closure member and foldable inwardly and laterally thereof, and coacting means carried by said wings and the frame for holding the wings extended when the closure member is in open position. 80

2. In combination with a window frame, a closure member for said frame, means for connecting an end portion of the closure member to the frame to permit said closure member to have swinging movement relative to the frame into open or closed position, wings pivotally connected to the side marginal portions of the closure member, coacting means carried by said wings and the frame for holding the wings extended 85 when the closure member is in open position, an additional wing hingedly connected with the inner portion of each of the first named wings, a chute plate hingedly connected to the lower portion of one of the second named 90 wings, and means for detachably connecting the lower marginal portions of the other of said second named wings with the chute plate when the wings are extended.

3. In combination with a window frame, a closure member for said frame, means for connecting an end portion of the closure member to the frame to permit said closure member to have swinging movement relative to the frame into open or closed position, wings pivotally connected to the side marginal portions of the closure member, coacting means carried by said wings and the frame for holding the wings extended when the closure member is in open position, an additional wing hingedly connected with the inner portion of each of the first named 100 wings, a chute plate hingedly connected to the lower portion of one of the second named wings, and means for detachably connecting the lower marginal portions of the other of said second named wings with the chute plate when the wings are extended, said 105 wings and chute plate folding one upon the other and upon the closure member when 110 compacted.

4. In combination with a window frame, a closure member for said frame, means for connecting an end portion of the closure member to the frame to permit said closure member to have swinging movement relative to the frame into open or closed position, wings pivotally connected to the side marginal portions of the closure member, coacting means carried by said wings and 115 120 125 130

the frame for holding the wings extended when the closure member is in open position, an additional wing hingedly connected with the inner portion of each of the first 5 named wings, a chute plate hingedly connected to the lower portion of one of the second named wings, means for detachably connecting the lower marginal portions of the other of said second named wings with 10 the chute plate when the wings are extended,

said wings and chute plate folding one upon the other and upon the closure member when compacted, and means for maintaining said parts in compacted relation when the closure member is in closed position. 15

In testimony whereof I hereunto affix my signature.

JAMES A. BROWN.
